UNITED STATES PATENT OFFICE.

JOHN A. HEBB, OF HOPWOOD, PENNSYLVANIA.

MINE-CAR BRAKING MECHANISM.

Application filed May 19, 1926. Serial No. 110,062.

My invention consists of an improvement in mine cars, and particularly in the braking mechanism therefor.

It has in view to provide means for braking the car from either end so as to avoid the necessity of standing on the front end of a car with the attendant risks.

Ordinarily, mine car brakes are operated through levers, cranks, and rigid pitmen, so that if a braking lever is mounted at either end of a car and connected with the brake shoe mechanism, operation of either lever will transmit undesired movement to the other, resulting in jamming or straining of the parts, or the necessity of releasing before action.

My invention obviates all such objections, and renders it possible to operate the brakes from either end, or at either side of either end of the car, without disturbing the other operative lever or levers.

I have shown the operating levers at each end portion of the car and at opposite sides thereof, connected to one or the other of two side levers which are capable of operation from either end, and each of which is mounted on a common cross rock shaft, whereby both of said levers operate together when either is actuated, in effecting simultaneous movement of the brake shoes, at opposite sides.

The present invention is an improvement on the general type of construction shown in prior Patent No. 1,508,971 granted to William J. McDade and myself, September 16, 1924.

In the drawings illustrating one preferred embodiment of the invention,—

Fig. 1 is a side view in elevation of a mine car provided with my improvement;

Fig. 2 is an end view of the same;

Fig. 3 is a perspective detail view showing the actuating mechanism, detached;

Fig. 4 is a detail view in side elevation of one of the side levers.

Referring to the drawings, 2 is the body of the car of usual design, mounted on wheels 3 and provided with a brake shoe 4 at each side of well known form.

Said shoes are mounted for vertical adjustment toward and from the wheels 3 by straps 5 which embrace the brake shoes 4 and are connected therewith by transverse bolts 6 or in any other suitable way. A guiding extension 7 of each strap member, for each brake shoe, extends upwardly through a

guiding bracket 8 secured to each opposite side of the car body, as in Figs. 1 and 2.

By such arrangement, with straps 5 mounted in a guiding slot of each bracket, each brake shoe may be maintained centrally between the wheels 3—3 so as to insure quick and even application of braking power, upon lowering the shoes, with equal simultaneous separation on raising.

For the purpose of operating the shoes together, either downwardly for braking or upwardly for release, I provide a pair of levers 9 secured to the opposite ends of a transverse rock shaft 10, mounted in suitable bearings across underneath the body of the car. Each lever 9 is provided with an outer lateral lifting terminal 11 and an upwardly extending lever arm 12, by which similar movement may be imparted to the lever, either by raising end 11, or by pulling end 12 in the opposite direction lengthwise.

For such purpose, a pair of levers 13 are pivoted at 14 at each opposite side of one end of the car, in suitable guides 15. Said levers are connected by their bell crank extensions 16 and chain sections 17, with the ends 11 of levers 9, so that when either lever 13 is thrust backwardly toward the end of the car, as at the left hand end of Fig. 1, the long arm terminal 11 of corresponding lever 9 will be raised.

Likewise the lever extension 12 is connected by rod 18 and chain section 19 with an ordinary straight lever 20, pivoted at 21, one at each opposite side of the other end of the car.

When either lever 20 is drawn toward the end, a similar movement will be imparted to one or the other arm 12 of lever 9, in the same manner described.

Levers 9 are operatively connected with the brake shoes 4 and their straps 5, by a slotted arm 22 engaging stud 23 as shown in Fig. 3.

With either application, by either lever 13 or 20, and with levers 9 keyed to the rock shaft, a similar rocking movement will be imparted to cross rock shaft 10, with a corresponding downward thrust of both arms 22, by which movement both brake shoes will be simultaneously applied. Upon release of either of such levers, the gravitating action of the outer end of levers 9 will act to lift the brake shoes away from contact, such motion being limited by the slack of either chain section 17 or 19.

By the construction shown and above described, the operator may apply braking action to the wheels while standing at the rear of the car, and operating the lever 13 or 20 at either side, with perfect safety and ample power, equally distributed through the several wheels.

The construction is very simple, cheap and effective, and provides a safe, powerful and directly acting equipment.

It may be applied to other than mine cars, and may be changed or varied from in different details by the skilled mechanic, but all such changes are to be considered as within 15 the scope of the following claims.

What I claim is:

1. The combination with a mine car having wheels thereon, of a braking mechanism therefor comprising a pair of vertically movable shoes adapted to be moved into wheel engaging position, a transverse rock shaft, a pair of levers secured to said rock shaft each operatively connected with one shoe, a hand lever at diagonally opposite corner portions 20 of the car, and means flexibly connecting each of said diagonally located levers with one of the rock shaft levers.

2. The combination with a mine car having wheels thereon, of a braking mechanism 30 therefor comprising a pair of vertically movable shoes adapted to be moved into wheel engaging position, a transverse rock shaft, a pair of levers secured to said rock shaft each operatively connected with one shoe and each 35 provided with two independently operating tension connections, and oppositely located hand levers connected to said levers by said connections.

3. The combination with a mine car having 40 wheels thereon, of a braking mechanism therefor comprising a pair of vertically movable shoes adapted to be moved into wheel engaging position, a transverse rock shaft, a pair of levers secured to said rock shaft each operatively connected with one shoe by pin 45 and slot connection, and a lever at each end of the car flexibly connected with one of said levers.

4. The combination with a mine car having 50 wheels thereon, of a braking mechanism therefor comprising a pair of vertically movable shoes adapted to be moved into wheel engaging position, a transverse rock shaft, a pair of levers secured to said rock shaft each 55 operatively connected with one shoe, and levers at each side of each end of the car flexibly connected with said levers.

5. The combination with a mine car having 60 wheels thereon, of a braking mechanism therefor comprising a pair of vertically movable shoes adapted to be moved into wheel engaging position, a transverse rock shaft, a pair of levers secured to said rock shaft each 65 operatively connected with one shoe and having an upwardly and a laterally ex-

tending arm, and actuating hand levers therefor mounted on the car and flexibly connected to said arms.

6. In a mine car, a vertically movable 70 brake shoe mounted for vertical movement between two adjacent wheels having a holding strap provided with a stud, a rock shaft, and an operating lever secured thereto having a plurality of divergently disposed connecting arms for independent connection with independently operative hand levers.

7. In a mine car, a vertically movable 75 brake shoe mounted for vertical movement between two adjacent wheels having a holding strap provided with a stud, a rock shaft, an operating lever secured thereto having a plurality of divergently disposed connecting arms, and a plurality of independently operative hand levers on the car, one of said levers being flexibly connected with each of 80 said arms.

8. In a mine car, a vertically movable 85 brake shoe mounted for vertical movement between two adjacent wheels having a holding strap provided with a stud and a guiding extension, a guide therefor, a rock shaft, an operating lever having pin and slot connection with the brake shoe and variably extending arms, and a hand lever at each end portion of the car flexibly connected with 90 one of said arms.

9. The combination with a mine car having 95 wheels thereon, of a braking mechanism therefor comprising a pair of vertically movable shoes each adapted to be moved into wheel engaging position between the wheels at opposite sides, a transverse rock shaft, a pair of levers secured to opposite end portions of said rock shaft each operatively connected with one of said shoes and each having plural power applying arms, and individual actuating hand levers therefor mounted on the side of the car and flexibly connected to said arms.

10. The combination with a mine car having 100 wheels thereon, of a braking mechanism therefor comprising a pair of vertically movable shoes each adapted to be moved into wheel engaging position between the wheels at opposite sides, a transverse rock shaft, a 105 pair of levers secured to opposite end portions of said rock shaft each operatively connected with one of said shoes, and an actuating hand lever mounted on the side of the car and connected to one of said levers.

11. The combination with a mine car having 110 wheels thereon, of a braking mechanism therefor comprising a pair of vertically movable shoes each adapted to be moved into wheel engaging position between the wheels at opposite sides, a transverse rock shaft, a 115 pair of levers secured to opposite end portions of said rock shaft each operatively connected with one of said shoes, and an actuating hand lever at diagonally opposite 120

125

130

corner portions of the car connected to one of said levers.

12. The combination with a mine car having wheels thereon, of a braking mechanism therefor comprising a pair of vertically movable shoes each adapted to be moved into wheel engaging position between the wheels at opposite sides, a transverse rock shaft, a pair of levers secured to opposite end por-

tions of said rock shaft each operatively connected with one of said shoes, and an actuating hand lever at each corner portion of the car flexibly connected with one of said arms.

In testimony whereof I hereunto affix my signature.

JOHN A. HEBB.
